MAIL BAG

George C. Lester, Buffalo, N. Y.

Application September 17, 1938, Serial No. 230,467

1 Claim. (Cl. 150—11)

This invention relates to improvements in bags of the kind which are closed by draw cords, or straps, and proposes a bag which, although not necessarily limited to such use, is characterized by features which render it of particular utility in connection with the handling of mail, particularly parcel post.

Mail bags which are now in use have draw cords which are threaded in and out through a series of openings formed in the side walls of the bags around their open ends, alternate sections of the cords being located on the outside of the bags while the intermediate connecting sections are located on the inside. Such draw cords have the objection that when a bag is turned upside down and emptied in conventional manner it frequently happens that a piece of mail will be caught between an interior section of the draw cord and the side wall of the bag and be mutilated as an incident to the further efforts which are made to remove it or, in some instances, be inadvertently overlooked and permitted to remain in the bag.

The principal object of the present invention is to overcome the above objections, this object contemplated a novel design of bag wherein provision is made for accommodating the draw cord, or strap, in such a manner that it is located wholly exteriorly of the bag.

30 A further object is to provide for the reinforcing of those portions of the bag which carry the draw cord, or strap.

The invention is illustrated in the accompanying drawing in which:

35 Figure 1 is a perspective view of a bag embodying the features of the invention.

Figure 2 is a section through the bag and is taken along line 2—2 of Figure 1.

Figure 3 is a section taken along line 3—3 of

40 Figure 2.

The bag, which is preferably of conventional shape, may be made of any suitable material. In accordance with the invention it is formed with a series of lengthwise extending fin-like flaps 5 which are produced by gathering the material of the bag to form pleats or folds and stitching the inner edges of the latter as indicated at 6. The flaps 5 are preferably triangular in shape, their upper wide ends being conterminous with the 45 open end of the bag and their lower ends merging

with the body portion of the bag. Openings 1 (Figure 3) are formed in the wide ends of the flaps 5 to accommodate a draw cord 8, the said openings preferably being reinforced in conventional manner by eyelets 9. The flaps 5 may be 5 spaced around the bag in any desired manner. As shown, and preferred, however, the two flaps which carry the terminal portions of the draw cord are formed alongside one another in order to facilitate manipulation of the cord in closing 10 and opening the bag. It is understood, of course, that the ends of the cord 5 may carry a conventional lock for preventing accidental or unintentional opening of the bag when it has once been closed. Suitable openings 10 (reinforced by 15 eyelets 11, if desired) may be formed in the bag between the flaps 5, whereby to enable the bag to be hung upon the hooks of racks or other supporting means.

Referring particularly to Figure 2, it will be 20 noted that the mouth of the bag is the same size as the body portion, the stitched inner edges of the flaps 5 being collinear with the walls of the body portion of the bag. It will be apparent, therefore, that, as a result of this and 25 the fact that the draw cord is located wholly exteriorly of the bag, the mouth of the latter when open is unobstructed. Hence the possibility of a piece of mail or other article remaining in the bag or being mutilated when the bag is emptied 30 is prevented.

The flaps 5 have further advantages. They strengthen the sides of the bag and, owing to their double thickness, they reinforce those portions of the bag which are acted upon by the 35 draw cord when the latter is tightened or loosened.

I claim as my invention:

A bag having excess material at the mouth end formed into a series of spaced folds or pleats 40 which extend lengthwise of the bag, the inner edges of said folds or pleats being substantially collinear with the side walls of the body portion of the bag and being permanently secured together so that they cannot separate when the 45 bag is opened, openings formed in said flaps outwardly of said edges and a draw element threaded through said openings which is adapted to be loosened to open the bag and tightened to close it.

GEORGE C. LESTER. 50
